N. O. GOLDSMITH,
FROG.
APPLICATION FILED JUNE 9, 1917.

UNITED STATES PATENT OFFICE.

NATHANIEL O. GOLDSMITH, OF NORWOOD, OHIO, ASSIGNEE TO THE WEIR FROG COMPANY, OF NORWOOD, OHIO, A CORPORATION OF OHIO.

FROG.

1,246,418.

Specification of Letters Patent. Patented Nov. 13, 1917.

Application filed June 9, 1917. Serial No. 173,724.

To all whom it may concern:

Be it known that I, NATHANIEL O. GOLDSMITH, a citizen of the United States, and a resident of Norwood, in the county of 5 Hamilton and State of Ohio, have invented certain new and useful Improvements in Frogs, of which the following is a full, clear, and exact description, reference being had to the accompanying drawings, 10 forming part of this specification.

My invention relates to frogs or crossings, particularly those to be employed in railroad work, where the strains are much greater than in street railroads. It also 15 relates to insert frogs or crossings in which the insert is made of some hard metal such as manganese steel, such frogs being called manganese insert frogs.

There are two most important points in 20 insert frog construction, first, that the insert be securely bolted in between the rails of the frog so as to be perfectly tight, and, second, that the bolts should stay tightly in place, both of which are difficult because the bolt 25 holes in the insert cannot be accurately gaged in casting the piece and the insert will thus work loose quite rapidly.

I am aware that the use of a soft metal to 30 secure the hard wearing plate in a manganese frog or crossing has been employed. Especially is this true in the case of crossings or frogs used in traction lines, in which the manganese insert has been placed in a casting and after it is wedged up to the 35 proper location, molten zinc has been poured around the retaining casting and the manganese insert for the purpose of securing this insert in place. This construction, however, forms a bed of soft metal under the 40 manganese insert, which merely rests upon a narrow bearing afforded by the wedges.

In some constructions, the manganese insert has been bolted to the casting and soft metal poured around the nuts of the bolts 45 and under the insert for the purpose of preventing the nuts on the bolts shearing loose and forming a bed for the insert.

My invention differs from this in that no attempt is made to secure a soft metal 50 bearing between the manganese casting and the rail base, nor has any attempt been made to prevent the nuts on the bolts getting loose by means of soft metal poured around the bolts. The principal object I desire to 55 cure is an inexpensive means of preventing

the insert casting from moving between the rails. The purpose of the soft metal poured around the bolts is to rigidly maintain the location of the parts in the frog, so that no movement of the casting in the frog and 60 between the rails will result when a wheel passes over the frog.

I have found, however, a way of constructing a frog or crossing which will take advantage of the feature of drawing the insert tightly into place between the rails of the frog with the bolts, and still permits of zincing the bolts in place after the frog has been tightly bolted together. 65

This object I accomplish by that certain 70 construction and arrangement of parts to be hereinafter more specifically pointed out and claimed.

In the drawings,

Figure 1 is a top plan view of a frog 75 illustrating my invention.

Fig. 2 is a like view of a modified form of insert for the frog shown in Fig. 1.

Fig. 3 is a sectional view taken on the line 2, 2, of Fig. 1. 80

The frog is of the usual construction, and it should be understood that the frog proper forms no part of this invention. Neither is the invention applicable only to frogs, since in switches, crossings and all kinds of 85 special rail parts where hard metal inserts can be used, the invention is as readily applicable.

The frog as illustrated has the wing rails 1, 1, and the guard rails 2, 2, between which 90 is the insert 3. The insert is made of hard metal, such as manganese steel, and is formed so as to fit the space between the rails of the frog structure.

In the case of a crossing, the insert would 95 not, of course, be shaped in the same manner, but would be shaped so as to fit between the rail parts to be assembled together. As shown in Fig. 3, the rails of the frog have webs 4 between which and the balls and 100 bases of the rails the insert fits.

Running through the insert and the rails are bolt holes 5, 5, for the insert, and 6, 6, for the rails, and set in these holes are the bolts 7. The operations in putting the frog 105 together, which is done before shipment, are to set the insert into the web space of the rails and turn up the bolts so as to draw the rails and insert together, with the insert clamped into the web space. 110

As shown, the inserts are made of the full width of the space between the rail members of the frog, and when the parts are bolted together, there is a contact at the abutting 5 points between the rails and the insert which is fast and tight, since the insert fills the entire space between the rails. Also the insert is made with a base 8 to fit against the extending bases of the rails and a shoulder 9 10 to fit under the ball of the rails, so that it is held against vertical movement dependent upon the closeness of the fit and the tightness with which the bolts are turned up in assembling.

15 In the one form of frog (Fig. 1), there are cut in the sides of the insert the narrow slots or grooves 10. These cuts are made to lead into the bolt holes of the insert, and the bolt holes are made to loosely receive the 20 bolts.

After the frog is assembled, some soft metal binder 10^a is poured into the slots and runs through them into the bolt holes of the insert, thereby binding the bolts in place 25 and preventing their jarring under the most trying usage.

In another form of insert, the slots are made wider as at 11, leaving the original sides of the insert in the form of pads 12 30 which abut against the rail members of the frog when assembled. The soft metal in this instance will flow into the bolt holes through the spaces 11 intermediate the pads, and it will also serve some function in holding 35 the parts of the frog together at the sides.

The second form of insert is not perhaps as valuable as the first, since there is not so much of an abutment of the insert to the 40 rails. In each case, the frog may be completely assembled in finished form and bolted tight, before any soft metal is poured into the structure. And in each case the structure is a bolt-held frog with the bolts 45 zinced to keep them in place in the cored holes of the insert.

I am aware, as stated, that zinc or other soft metal binder has been used in frog construction, but in the uses with which I am 50 familiar, the inserts were laid in a bed of soft metal between the rail members of the frog, and although bolts may have been used, they really served no function, since the frog was bound together without them and the tightening of them could not be 55 done effectively because they were bound in with the soft metal before they were turned up.

Having thus described my invention, what 60 I claim as new and desire to secure by Letters Patent, is:—

1. In a frog switch or crossing, rail mem-

bers, and an insert member having bolt holes, bolts for tightly securing the insert between the rail members, said insert being 65 formed with passageways so as to permit the flowing of soft metal into the bolt holes after the said device is assembled and the bolts tightened in place.

2. In a frog switch or crossing, rail members, and an insert member having bolt holes of larger size than the bolts to be used, bolts passing through the rails and insert and tightly turned up, and grooves in the insert running to the bolt holes to permit of 75 flowing soft metal into the bolt holes after the assembly of the said device.

3. A frog switch or crossing, comprising rail members, and an insert member, said insert member being formed so as to fill the 80 space between the rail members, and abut the balls of the rails at the one side and the bases of the rails at the other fitting tightly therein, bolt holes in the rail members and the insert, and passages in the insert leading 85 to the bolt holes, for flowing soft metal into the bolt holes after the assembling and tightening of the device.

4. In a frog switch or crossing, rail members, and an insert member having bolt 90 holes of larger size than the bolts to be used, bolts passing through the rails and insert and tightly turned up, and grooves in the insert running to the bolt holes to permit of 95 flowing soft metal into the bolt holes after the assembly of the said device, said grooves being in the edge of the insert and reduced in width so as to cut out the least possible amount of the abutting side portions of the 100 insert.

5. In a frog or the like, rail members having balls, flanges and bases, an insert to fit between said rail members and shaped to conform at the sides to fit into the webs of the rails and present shoulders to the balls and bases, bolt holes in the rail members and insert, bolts in the holes, and interspaced 105 passages in the insert leading to the bolt holes, whereby the bolt holes may be zinced after assembly of the frog.

6. In a frog or the like, rail members having balls, flanges and bases, an insert to fit between said rail members and shaped to conform at the sides to fit into the webs of the rails and present shoulders to the balls and bases, bolt holes in the rail members and insert, bolts in the holes, and interspaced 115 passages in the insert leading to the bolt holes, whereby the bolt holes may be zinced after assembly of the frog, said passages 120 comprising narrow grooves cut in the sides of the insert.

NATHANIEL O. GOLDSMITH.
